WINDOW SHADE RAISING DEVICE

Warren S. Pickett, Santa Clara, Calif.

Application April 16, 1934, Serial No. 720,900

2 Claims. (Cl. 156—27)

This invention relates to improvements in curtain fixtures and has particular reference to a slidable bracket for supporting window shades at any desired point.

5 The principal object is to provide a shade roller bracket for swinging windows whereby the shade may be moved with respect to the window pane for the purpose of washing, painting, etc.

A further object is to produce a device which 10 is simple to operate and one which may be readily adjusted.

A still further object is to produce a device which is economical to manufacture.

Other objects and advantages will be apparent 15 during the course of the following description.

In the accompanying drawing forming a part of this specification and in which like numerals are employed to designate like parts throughout the same,

20 Fig. 1 is a front elevation of a window having my invention applied thereto,

Fig. 2 is a side elevation of Fig. 1,

Fig. 3 is a side elevation of one of the brackets,

25 Fig. 4 is a side elevation of the other of the brackets,

Fig. 5 is an enlarged end elevation of one of the brackets,

Fig. 6 is an enlarged fragmentary detail view 30 showing the manner in which the bracket supports the end of the shade and roller, and

Fig. 7 is a fragmentary perspective view of the 35 bracket supporting track.

It has been customary to mount window shades directly against the bottom of the window sash and consequently when the windows are cleaned, the shade must be removed or else the bottom portion of the glass cannot be properly washed, and also the shade is liable to become soiled in the washing operation. Applicant has, therefore, 40 devised a simple bracket whereby the shade may be moved along the edge of the window so as to expose any portion of the pane.

In the accompanying drawing wherein for the 45 purpose of illustration is shown a preferred embodiment of my invention, the numerals 5 and 6 designate the upper and lower window panes of swinging type sash windows, the frames being designated by the numerals 7 and 8. As the mounting on both window sashes are identical, but 50 one will be described. Referring to the sash 8, it will be noted that parallel tracks 9 and 11 are secured to the vertical sides of the sash and by viewing Figs. 6 and 7 it will be noted that these tracks have inturned edges 12 and 13 and a central raised portion 14. This construction forms 55 channels 16 and 17 and it will be here noted that

the channel 17 is wider than the channel 16. This is to permit the brackets 20 to move as indicated in dotted lines of Fig. 6. Each bracket is identical, with the exception that with one form of bracket a hole 19 is provided and in the other a slot 21 is provided, the purpose of this hole in one and slot in the other is to engage the customary supporting ends of the shade roller A.

5 By viewing Fig. 5 it will be noted that the brackets 20 are really bent from a sheet of metal 10 so as to provide a V-portion 22 having its legs bent as shown at 23 and 24. Therefore, these portions 23 and 24 will slide in the channels 16 and 17. The portion 24 has a pin 26 extending therefrom, which is capable of engaging holes 27 formed 15 in one side of the tracks (see Fig. 7).

The manner of using my device is as follows:—

The tracks are first placed upon the window frames parallel to each other and secured in this position. A bracket is mounted in each of the 20 tracks and a shade roller positioned therebetween. By now squeezing the brackets so as to release the pins 26 from the holes 27, the shade may be moved up or down with relation to the bottom of the window and after being properly 25 adjusted release of the brackets will cause the pins 26 to engage the openings 27, thus holding the shade in adjusted position.

It is to be understood that the form of my 30 invention herewith shown and described is to be taken as a preferred example of the same and that various changes relative to the material, size, shape and arrangement of parts may be resorted to without departing from the spirit of the invention or the scope of the subjoined claims. 35

Having thus described my invention, I claim:—

1. In a device of the character described, the combination with a track mounted upon a side of a window, a movable bracket mounted in said track adapted to support an end of a shade 40 roller, means for adjusting the position of said bracket in said track, said means including a removable pin extending through said track and into said bracket.

2. In a device of the character described, a 45 track secured to a window frame, said track being parallel to a similar track, said track having channels formed therein, a bracket having feet of approximate uniform width mounted in the respective channels of said track and slidably in 50 said channels, one of said channels being wider than the other whereby said bracket may be disengaged from said channel for the purpose of adjusting said bracket longitudinally of said channel. 55

WARREN S. PICKETT.
